UNITED STATES PATENT OFFICE.

JOHN R. MITCHELL, OF CHICAGO, ILLINOIS, ASSIGNOR TO WILLIAM H. MINER, OF CHAZY, NEW YORK.

YOKE FOR DRAFT-RIGGINGS.

1,255,908.

Specification of Letters Patent. Patented Feb. 12, 1918.

Application filed July 6, 1915, Serial No. 33,110.

To all whom it may concern:

Be it known that I, JOHN R. MITCHELL, a citizen of the United States, residing at Chicago, in the county of Cook and State 5 of Illinois, have invented a certain new and useful Improvement in Yokes for Draft-Riggings, of which the following is a full, clear, concise, and exact description, reference being had to the accompanying drawings, forming a part of this specification.

This invention relates to improvements in yokes for draft riggings.

An object of the invention is to provide a yoke for draft riggings of the hooded type 15 wherein simple and effective means are employed to securely unite the hood or head with the yoke strap.

In the drawing forming a part of this specification, Figure 1 is a part section, part 20 side elevation of a yoke showing one embodiment of my invention. Fig. 2 is a transverse vertical section taken on the line 2—2 of Fig. 1. Figs. 3 and 4 are views similar to Fig. 1, but illustrating different methods 25 of carrying out my invention, in each of said figures the rear portion of the strap being broken off.

In said drawing referring to Figs. 1 and 2, A denotes the hollow substantially rectangular head or hood within which is adapted 30 to be received the butt of a draw bar 10. In the construction shown, the hood and draw bar are connected by means of a coupler key 11, the latter extending through slots in the 35 side-walls 12—12 of the hood. At the top and bottom, the hood or head A is provided with longitudinally arranged slots 13—13, each having a plurality of offset portions 14—14 and a corresponding number of depressions or grooves 15—15, the latter aligning with perforations 16 in the sides of the 40 hood.

The yoke strap is designated by the reference B, the same being of substantially U 45 shape and having upper and lower arms 17 and 18, the outer ends 19—19 of which are positioned within the slots 13—13.

In manufacturing my improved yoke, the hood A is formed with the slots 13, grooves 50 15 and perforations 16, as shown. The ends of the strap B are preferably heated and inserted within the slots of the hood whereupon the pins or rivets 20—20 are driven through the perforations 16 and recesses 15, 55 thereby displacing the metal of the ends 19

to fill the offset portions 14, as indicated at 21—21. The connection between the strap and the hood thus provided is strong and prevents the hood being pulled off of the strap under load.

In the modification shown in Fig. 3, the hood A¹ is provided with upper and lower slots 113, each of said slots having merely a single offset or depression 114, and only one pin 120 being used to secure the ends 119 of 60 the yoke strap.

In Fig. 4, the structure there illustrated comprises a hood or head A², having upper and lower slots 213, each of the latter having two offsets or depressions 214 oppositely arranged, that is, one on one side of the slot and the other on the opposite side thereof. Recesses 215 to receive the pins 220 are provided, one opposite each offset 214. The pins 220 are applied in the same manner as 70 the pins 15, with the result that the ends 219 of the yoke strap are bent or displaced so as to form an ogee curve.

From the preceding description it will be 80 seen that in each instance the means of connecting the hood and strap involves the offsetting or displacement of portions of the yoke strap, these portions of the strap being forced into corresponding offsets or depressions in the walls of the slots in the hood. 85 Also, corresponding to each offset or depression in the slots of the hood are ribs or projections, either integral or removable, by which the offsetting of the metal of the straps is accomplished. In each modification 90 it is furthermore evident that a tortuous passage is formed in the hood to receive a correspondingly shaped section of metal forming the ends of the strap, thereby preventing the separation of the strap and 95 hood under tension.

One of the advantages of my improved arrangement lies in the fact that the connection between the strap and the hood is made without removing or losing any of the metal 100 of the strap, such as is necessary where rivets to pierce the strap are employed. In other words, my improved structure always retains the full, effective strength of the strap.

I claim:

1. A yoke for draft riggings comprising, a hollow head having slots extending longitudinally therethrough and a strap having the ends thereof seated in said slots, said 110

slots being so formed as to provide reversely curved passage ways and the ends of the strap being bent to conform to said reversely curved passage ways.

- 5 2. A yoke for railway draft riggings comprising, a hood adapted to be secured to a draw bar, said hood having longitudinally arranged slots through the top and bottom walls thereof, each of said slots being offset 10 intermediate its ends, a strap having the

ends thereof seated in said slots and bent to conform to the offset portions of said slots, and pins extending transversely through the head and engaging said straps on the inner sides of said offset portions thereof.

15

In witness that I claim the foregoing I have hereunto subscribed my name this 30th day of June, 1915.

JOHN R. MITCHELL.
